UNITED STATES PATENT OFFICE.

WILLIAM E. HUNT, OF OTTUMWA, IOWA, ASSIGNOR TO OTTUMWA BOX CAR LOADER COMPANY,
OF OTTUMWA, IOWA, A CORPORATION OF IOWA.

CAR-LOADER.

No. 895,089.

Specification of Letters Patent.

Patented Aug. 4, 1908.

Application filed October 14, 1907. Serial No. 397,360.

To all whom it may concern:

Be it known that I, WILLIAM E. HUNT, a citizen of the United States, residing at Ottumwa, in the county of Wapello and State of Iowa, have invented certain new and useful Improvements in Car-Loaders; and I do hereby declare the following to be a full, clear, and exact description of the invention, such as will enable others skilled in the art to 10 which it appertains to make and use the same.

This invention relates to improvements in an apparatus for loading cars, and more especially to the means employed for centering and holding the car in position while receiving its cargo.

The prime object of the invention is to provide a tilting platform, with bumpers mechanically, and simultaneously operated to 20 center the car, and means for automatically locking said bumpers in position.

The invention also relates to the automatic means employed for releasing the bumpers, and returning their carriages to normal position out of the way of the car, to permit the latter to be moved away from the apparatus.

In this class of car loaders it is usual to move a car on a tilted platform, under a chute approximately centrally disposed to 25 the car, and the latter is tilted to cause the cargo as it is delivered to fall by gravity toward one end. After approximately half the load is delivered, the car is raised to normal position and then tilted in the opposite direction to receive the remainder of the load, after which it is brought into a horizontal plane to be removed. The purpose of this operation is well known in this art, and is to do away with the necessity of shifting the 30 chute from one place to another in distributing the cargo. I do not claim broadly in this application means for accomplishing this result, but the means employed to make it more economical and convenient in handling 40 the apparatus.

The invention contemplates improvements in the details of construction and arrangement of parts, all of which will be hereinafter referred to and particularly pointed out in 45 the claims.

In the drawings forming a part of this specification, Figure 1 is a side elevation of my improved apparatus, showing a car centrally disposed in full lines, and the bumpers 55 in dotted lines, holding said car in position;

also showing in dotted lines the car and its platform tilted to receive the cargo. Fig. 2 is a top plan view of the apparatus. Fig. 3 is a transverse section of the apparatus. Fig. 4 is an enlarged detail view of one of the 60 bumpers and its carriage. Fig. 5 is a detail top plan view of the same.

1, indicates a well in which is a base 2, supporting idle rollers 3, supporting a tilting platform 4. The platform preferably consists of a pair of beams 5, carrying tracks 6, and a pair of segments 7, the latter traveling directly on the rollers 3, and thereby supporting the platform. Between the beams 5, are two I-beams 8, which form ways for a pair of traveling bumper carriages, to be herein-after described.

Supported in bearing mounted on the base is a transverse shaft 9, carrying sprocket wheels 10, around which and idlers 12, pass 75 chains 11, secured to the peripheries of the segments 7. On the outer end of shaft 9, is a sprocket wheel 13, around which passes a sprocket chain 14, also passing over a sprocket wheel 15, on the end of a shaft 16, 80 operated by a suitable engine located to one side of the apparatus.

On the shaft 9, is a brake-wheel 17, surrounded by a brake-band 18, connected to a lever 19, pivoted at its ends to a piston rod 85 20, operating in a cylinder 21. Steam, air or other means may be employed to operate the piston rod in the cylinder to control the brake.

Mounted in bearings at the ends of the well 90 1, directly under the ends of the beams 5, are upright levers 20^a, connected at their upper ends by links 21, with cranks 22, secured to shafts 23. At the outer ends of the shafts 23, are cranks 24, connected by a rod 25, pivoted 95 to a hand lever within convenient reach of the operator. The object of this connection is to provide a suitable support for the ends of the platform when it is in a normal position, as clearly shown in Fig. 1. When the hand lever is operated the cranks 22, tilt the supporting rods 20^a, outwardly from under the ends of the beams 5, to allow the latter to be tilted in the well.

The operation of the mechanism thus far described is substantially as follows: The operator starts the engine which revolves the shaft 16, and through the connections, the segments are caused to turn on the idle rollers 3, which in turn correspondingly tilts the 110

beams 5, the brake being at all times under the control of the operator, hence the tilting of the platform is likewise under perfect control. Of course it will be understood upon 5 the reversing of the engine and releasing of the brake the platform can be returned to normal position.

In alinement with the tracks 6, are track-sections 26, between which is formed an 10 opening 27, to receive the bumper carriages 28, when lowered upon the tracks 29. On each side of the openings 27, are fixed inclined tracks 29, terminating at their upper ends approximately in alinement with the I-beam 8, of the platform. Traveling on the 15 tracks 29, are carriages 28. Each carriage consists of a beam 30, provided with rollers 31, and 31^a, and supported by the beam is a standard 32, having at its upper end a bumper 33. Pivoted to the standard 32, at 20 34, is a bifurcated pawl 35, provided at its lower end with engaging points 36, and an intermediate roller 37.

Mounted on the segments 7, is a shaft 38, 25 having a sprocket wheel 39, intermediate the I-beams 8. Engaging opposite sides of the sprocket wheel are two rack-bars 40, extending in opposite directions toward the openings 27. To the outer end of each rack bar, is 30 connected an arm or arms 43, slotted at 44, to receive the journal of the roller 31^a, of the carriage 28. Pivotedly connected to the outer end of each arm 43, is a link 45, pivoted at its outer end to a wedge 46, which is 35 grooved in its under side to receive the web of the I-beam 30. The wedge is normally under the roller 37, as shown in Fig. 4.

On the shaft 38, is mounted a gear-wheel 50, meshing with a pinion 51, on a stub shaft 40 52, connected by universal joints 53, to a power shaft 54. Coöperating with the power shaft 54, is a clutch 55, by means of which the operator can control the movement of the bumper carriages.

45 After the car is moved on the platform 4, the operator throws the clutch 55, to communicate power to the shaft 38, which causes the gear wheel 39, to move the rack-bars 40, toward each other. During the first part 50 of the movement of the rack bars, the arms 43, move the distance of the slot 44, without moving the I-beams 30, which pulls on the links 45, to withdraw the wedges 46, out of the path of the rollers 37, thereby allowing the points 36, to drop sufficiently to engage the rack teeth 56, mounted on the beams 8. The continued movement of the rack bars 40, after the rear wall 57, of the slots 44, reaches the journals of the rollers 55 31^a, will draw the carriages bodily up the inclined tracks 29. As the movement of the carriages advances toward the center of the platform the rollers 31^a, will be directed in the ways formed between the I-beams 8, and the rollers 31, also traveling on the track

29, will when reaching the upper end of said track enter the ways between the said I-beams. When the carriages are in the ways the points 36, ride over the rack-bars 56, and catch in the teeth thereof. The two 70 bumpers are therefore drawn toward each other simultaneously from the time the movement is started, until they bump against each end of the car and center it. Obviously should the car not be exactly in 75 the center of the platform, and it is desirable, in fact necessary that it should be, the movement of the two bumpers will properly position it, and the pawls will automatically lock, and thereby hold the car in position. 80 The car having now been properly positioned and locked on the platform, it is tilted to load it as previously described. To automatically release the car and to return the bumpers to their normal position, the operator, 85 through the medium of the clutch 55, reverses the direction of movement of power shaft 54, which through the gear connection, revolves the sprocket wheel 39, hence moves the rack-bars 40, outwardly. During the 90 first part of this movement the arms 43, are moved the distance of the slot 44, which through the links 45, will force the wedges 46, under the rollers 37, and thereby disengage the pawl 35, from the rack teeth 56, 95 and immediately the end 60, of the slots 44, reaches the journals of the rollers 31^a, the carriages 28, will be moved in the ways toward the openings 27, and down the inclined track 29, until their normal position is 100 reached, as shown in full lines in Fig. 1. This position having been reached, the operator manually or otherwise operates the standards 20, provided of course the car has received its full cargo, and the car can then be 105 pushed from the platform.

From the foregoing description it will be observed that the two bumpers are under control of the operator, in their movement from normal to abnormal positions, or vice versa. Furthermore the mechanism for tilting the car is operated by the same engine which operates the bumpers.

The locking devices employed for fixing the bumpers, are automatically operated in 11 locking or unlocking the same, which saves considerable time on the part of the operator in loading cars. Furthermore they are so connected as to be simultaneously operated and are at the same time under perfect control.

The invention is exceedingly simple, and by reason of the comparatively few parts is durable in construction.

Having thus described my invention what I desire to secure by Letters Patent is—

1. In an apparatus of the class described, the combination of a tilting platform, bumpers operating at the ends of the platform between the rails thereon, and means for

simultaneously operating the bumpers from their normal position to operative position against a car on the platform.

2. In an apparatus of the class described, 5 the combination of a tilting platform, tracks carried by the platform, an inclined guideway at each end of the platform in alignment with the tracks, carriages carrying bumpers, and means for simultaneously drawing the 10 two bumpers up the inclined ways and on the tracks of the platform in operative position against a car on the latter.

3. In an apparatus of the class described, 15 the combination with a tilting platform carrying ways, a pair of bumpers at the ends of the platform, means for simultaneously operating the bumpers to move them from normal position to operative position against a car on the platform, and means automatically operated for locking the bumpers against 20 the car.

4. In an apparatus of the class described, 25 the combination with a tilting platform carrying ways, a pair of bumpers at the ends of the platform, means for simultaneously operating the bumpers to move them from normal position to operative position against a car on the platform, means for automatically locking the bumpers against the car, and automatically unlocking the bumpers previous 30 to their movement away from the car.

5. In an apparatus of the class described, 35 the combination with a tilting platform having ways, a bumper located adjacent each end of the ways on the platform, a locking device, means for operating the bumpers, including means for operatively positioning the locking device previous to movement of the bumpers.

40 6. In an apparatus of the class described, the combination with a tilting platform having ways, a bumper located adjacent each end of the ways on the platform, a locking device, means for operating the bumpers, 45 including means for operatively positioning the locking device previous to movement of the bumpers, said means also serving to release the locking device previous to the movement of the bumpers to their normal position.

50 7. In an apparatus of the class described, the combination of a tilting platform, a rack bar on the platform, bumpers located adjacent each end of the platform, pawls carried by the bumpers to engage the rack bars, means for simultaneously positioning the bumpers adjacent a car on the platform, the pawls engaging the rack bars to lock said bumpers in position.

60 8. In an apparatus of the class described, 55 the combination of a tilting platform, a rack bar on the platform, bumpers located adjacent each end of the platform, pawls carried by the bumpers to engage the rack bars, means for simultaneously positioning the

bumpers adjacent a car on the platform, the pawls engaging the rack bars to lock said bumpers in position, and automatic means for releasing the pawls when moving the bumpers away from a car.

70 9. In an apparatus of the class described, the combination of a tilting platform, means for tilting the platform, ways on the platform, a wheel having teeth mounted in the ways, a pair of rack bars engaging the teeth of the wheel, a pair of bumpers connected to the rack bars, and means operating the wheel to draw the bumpers in the ways in operative position against a car on the platform.

75 10. In an apparatus of the class described, the combination of a tilting platform, means for tilting the platform, ways on the platform, a wheel having teeth mounted in the ways, a pair of rack bars engaging the teeth of the wheel, a pair of bumpers connected to the rack bars, means operating the wheel to draw the bumpers in the ways in operative position against a car on the platform, means slidably connecting the rack bars and the bumpers, and means for automatically locking the bumpers in operative position 80 against a car.

85 11. In an apparatus of the class described, the combination of a tilting platform, means for tilting the platform, ways on the platform, a wheel having teeth mounted in the ways, a pair of rack bars engaging the teeth of the wheel, a pair of bumpers connected to the rack bars, means operating the wheel to draw the bumpers in the ways in operative position against a car on the platform, means slidably connecting the rack bars and the bumpers, means for automatically locking the bumpers in operative position 90 against a car.

95 12. In an apparatus of the class described, the combination with a platform comprising beams carrying tracks to support a car, segments attached to the beams, chains engaging the peripheries of the segments, a shaft located adjacent the segments, sprocket wheels mounted on said shaft, and around 100 which the chains pass, means operating the shaft to turn the segments to tilt the platform, a bumper at each end of the platform, means for operating the bumpers to position the same against a car on the platform, and 105 means for locking the bumpers.

110 13. In an apparatus of the class described, the combination with a platform, means for tilting the platform, means for supporting the platform at its ends when in normal position, a sliding bumper located adjacent one end of the platform, means for automatically locking the bumper in position against a car, means for positioning the bumper against the 115 car including a device for automatically set- 120

125 139

ting and releasing the locking means previous to the movement of the bumper in either direction.

14. In an apparatus of the class described, the combination of a tilting platform, means for tilting the platform, a bumper at each end of the platform, said bumpers being slidably mounted in wells or depressions adjacent to the ends of the platform, and means including a member carried by the platform and connected with the bumpers for positioning the latter against the ends of a car on said platform.

15. In an apparatus of the class described, the combination of a tilting platform, means for tilting the platform, a bumper at each end of the platform, means for operating the bumpers, a motor, the platform operating means and the bumper operating means being operated by said motor.

16. In an apparatus of the class described, the combination of a tilting platform, means for tilting the platform, inclined ways adjacent the ends of the platform, a carriage adapted to travel on each inclined way, a bumper mounted on the carriage which is normally below the plane of the top of the platform, a pawl carried by each bumper, rack bars carried by the platform, a wedge adjacent each bumper and slidable thereon, a loose connection between the rack bars and the wedge, a locking device on each bumper connected with the wedge, means for operating the rack bars, the loose connection permitting withdrawal of the wedges to position the locking device previous to movement of said carriages by their operating means.

17. In an apparatus of the class described,

the combination of a tilting platform, means for tilting the platform, inclined ways adjacent the ends of the platform, a carriage adapted to travel on each inclined way, a bumper mounted on the carriage which is normally below the plane of the top of the platform, a pawl carried by each bumper, rack bars carried by the platform, a wedge adjacent each bumper and slidable thereon, a loose connection between the rack bars and the wedge, a locking device on each bumper connected with the wedge, means for operating the rack bars, the loose connection permitting withdrawal of the wedges to position the locking device previous to movement of said carriages by their operating means, said means permitting of the forcing of the wedges under the locking devices to release the same previous to moving the carriages away from a car.

18. In an apparatus of the class described, the combination of a tilting platform, a pair of beams carried by the platform to form ways, a carriage adjacent each end of the platform including supporting rollers, ways adjacent the platform on which said rollers travel previous to engaging the ways between the beams of the platform, bumpers carried by said carriages, rack bars, and means for operating said rack bars to move said bumpers in the ways on the platform.

In testimony whereof, I have signed my name to this specification in the presence of two subscribing witnesses.

WILLIAM E. HUNT.
